COIN ACTUATED CONTROL MECHANISM

Victor G. Smith, Detroit, Mich., assignor to
Ex-Cell-O Corporation, Detroit, Mich., a corporation of Michigan

Application June 29, 1944, Serial No. 542,708

4 Claims. (Cl. 194—10)

1

This invention relates to coin actuated control mechanism for vending machines or the like.

In coin controlled vending machines a purchaser may obtain an article of purchase by inserting a coin, token or, in some cases, a plurality of coins such as a nickel and a dime. These are manufactured to receive a definite coin and will only operate by the insertion of that particular coin. If the machine is set to operate by the insertion of a dime, it will not operate by inserting two nickels, ten pennies or a nickel and five pennies. Thus, the purchaser is required to have the exact coin regardless of whether he has the required cash in different denominations.

It is, therefore, an important object of this invention to provide a coin actuated mechanism for vending machines or the like which will operate by the insertion of the price of the article regardless of the denominations of the coins. For example, if the article costs ten cents, the purchaser may operate the machine by either a dime, two nickels, ten pennies, or a nickel and five pennies.

Another object of the invention is to provide coin actuated control mechanism which, by simple adjustment, may be changed to be operated by a given amount at one time and another amount at another time. If the article costs ten cents at one time, the mechanism could be set to operate by the insertion of ten cents and, if the price of the article became twelve cents, the mechanism could be adjusted to be operated by the insertion of twelve cents, regardless of the denomination of the several coins totaling the given amount.

A further object of the invention is to provide coin actuated control mechanism embodying an improved coin return arrangement which will permit a return of the coins at the option of the operator at any time prior to the deposit of the last coin required to make up the sales price of the purchased item.

Other objects and advantages of the invention will be more fully understood from the following description taken in connection with the accompanying drawings in which:

Fig. 1 is a front elevational view of a vending machine equipped with a coin actuated control mechanism embodying a form of my invention.

Fig. 2 is an enlarged, fragmentary, sectional view taken on line 2—2 of Fig. 1 showing a portion of the machine and the operating mechanism of the control mechanism.

Fig. 3 is an enlarged sectional view taken on line 3—3 of Fig. 2.

Fig. 4 is a front elevational view showing the

control instruments mounted on the inside of the front panel.

Fig. 5 is an enlarged view of the coin counters illustrating diagrammatically the arrangement of coin chutes and the general location of control switches for controlling electrical circuits by which the lock release mechanism is actuated.

Fig. 6 is a wiring diagram illustrating the various electrical circuits for operating the machine; and

Figs. 7 to 11 inclusive are wiring diagrams illustrating the various combinations of switches which must be closed by various combinations of coin denominations before the release mechanism can operate.

Referring more particularly to the drawings, the invention has been illustrated therein as embodied in a coin actuated control mechanism applied to a vending machine. By way of preliminary to description of the coin actuated control mechanism itself the illustrated form of vending machine will first be described. It will be appreciated by those skilled in the art, however, that coin actuated control mechanisms embodying the present invention may be applied to a variety of different forms of vending machines or the like. In the particular vending machine shown a cabinet 10 is provided having an article containing compartment 12. A hinged lid 14 is arranged on the upper surface of the cabinet and is preferably provided with transparent panels 16 to permit purchasers to see the articles in making a selection. The bottom 18 of the compartment 12 is arranged on an incline with respect to the base of the cabinet 10 to permit the articles therein to be fed by gravity to the lower edge of the bottom 18 and to the front of the cabinet.

The upper surface of the bottom 18 is provided with a plurality of channel shaped trays 20 for the reception of aligned articles, which in the illustrated form are cartons 22 containing a perishable food product, such as milk.

The compartment 12 has its walls insulated as indicated at 24 and the transparent panels 16 are preferably made of spaced glass panels providing a dead air space 26 for insulating the upper portion of the compartment 12. Cooling coils 28 are arranged in the bottom 18 and are connected to a refrigerating unit (not shown) through conduit 32. A drain 34 is arranged in the lower corner of the compartment 12 to remove any condensation which might be formed therein.

The vending machine illustrated is particularly adapted for dispensing milk containers 22 arranged in rows for sliding movement in the

trays 20. At the lower edge of the bottom 18 and in the line with the trays 20, are dispensing members 36 in the form of receptacles with an open side facing the containers 22 for the reception of a single container at the lower end of each row of containers.

The dispensing members 36 are slideable into and out of the compartment 12 in a plane normal to the plane of the trays 20; openings 38 being provided in the upper face of the cabinet 10 through which the dispensing members extend. The upper ends of the dispensing members 36 are provided with caps 40 which seal the openings 38 when the members are within the compartment. Handles 42 are secured to the caps 40 for the purpose of withdrawing the dispensing members 36 from the cabinet 10.

The bottom of each dispensing member 36 is normally flush with the bottom of the inclined trays 20 so that the lower carton of each row is received in the dispensing member through its open side. When the dispensing member 36 is removed from the compartment 12, a carton is accessible to a purchaser through the open side as indicated in dotted lines of Fig. 2.

The dispensing members 36 are guided by downwardly extending rods 44 secured to the bottom of the members 36 adjacent their rear or open sides. These rods serve as stops for the cartons, preventing downward movement of the row when the members are withdrawn from the compartment 12.

A bracket 46 extends transversely of the cabinet and is secured to the sidewalls by bolts 48 securing the bracket 46 to angle members 50 secured to the sidewalls. The bracket 46 is provided with upper and lower bearings 52 and 54 respectively which receive the rods 44.

Journalized in the bracket 46 is a transverse lock bar 56 having oscillatory movement in end bearings 58. When the dispensing members 36 are in the compartment 12, the bar 56, in its position shown in the drawings, engages notches 66 in the rods 44, locking all dispensing members against removal. When the proper coin or coins are inserted in the coin controlled mechanism, the bar 56 is free for oscillation. When one rod is moved longitudinally, the bar 56 is swung out of the path of the notches 66. This unlocks all dispensing members so that any one may be selected and withdrawn.

In order to prevent the purchaser from selecting and withdrawing more than one dispensing member by a single operation of the coin controlled mechanism, there is provided an interlocking means which operates to lock all members except the one selected and partially withdrawn from the compartment. The movement of any one member causes locking of all other members.

The bracket 46 is provided with a channel track 68 open toward the rods 44. A plurality of balls 70 are received in the track 68. These balls 70 are of a diameter substantially equal to the diameter of the rods 44. The track 68 is arranged with respect to the rods 44 such that the balls intersect the rods 44. Notches 72 are provided in the rods 44 to permit the balls 70 to pass the rods 44 when moved transversely thereof in the track 68.

Referring to Fig. 3, the end walls 74 of the track 68 are arranged in such a manner, with respect to the end rods, that when the balls contact the end walls, the center of the ball does not pass beyond the center of the rod. The number of balls in the track are such that a space, indicated

at 76, is provided. This space is of a dimension to permit one of the rods to pass between adjacent balls. When the balls 70 are in a position as shown in Fig. 3, one rod such as the rod 44a is free for movement and by its movement it causes the balls to spread into the path of all other rods, thereby locking them against movement by the balls engaging the notches 72.

It will be understood that when all of the dispensing members 36 are within the compartment 12, and unlocked by the lock bar 56, any one may be withdrawn regardless of the position of the balls 70 and that such withdrawal movement causes the selected rod to move the intercepting ball out of its notch, crowding the other balls to the left or right into tight engagement locking all other dispensing members against withdrawal. As long as one of the rods 44 is withdrawn, or partially withdrawn, that rod retains the bar 56 in its unlocked position. When the rod is returned to its closed position, the bar 56, under tension (by a spring not shown) to rotate in a counterclockwise direction, falls in the notches 66 and automatically resets the coin controlled locking mechanism.

Means has been provided to prevent the return of the dispensing member 36 into the compartment 12 until the dispensing member has reached its fully withdrawn position. This means comprises a wedge 78 carried in a notch 80 in the bracket 46. One end of the wedge 78 is journaled in the notch 80 and its opposite end is received in a notch 82 in the rod 44 when the rod is in its locked position. A compression spring 83 urges the wedge toward the rod 44. As the rod is moved outwardly, the wedge is swung upwardly with its free end in dragging engagement with the surface of the rod, when the rod is moving outwardly; but it is in binding engagement with the rod if attempt is made to move the latter in the opposite direction. At the end of the rod 44 is a removable clip 84 which engages the wedge 78 and limits the outward movement of the dispensing member when the rod is withdrawn to its outmost position. A notch 86 is provided to permit the wedge to drop below a position normal to the axis of the rod 44 so that the rod may be moved inwardly without binding on the wedge.

The bar 56 is normally held in the position shown on the drawings by a spring not shown, and is provided with a locking member 100 which is rotatable therewith. The locking member is provided with a notch 102 which receives a plunger 104. When the plunger 104 is in the notch 102, the bar 56 is held against rotation and the rods 44 are locked by the bar 56 engaging the notches 66 in the rods 44.

Referring now to the coin controlled mechanism embodying the present invention and herein illustrated as utilized for unlocking the rods 44, I have shown a solenoid S1 which when energized, retracts the plunger 104 from the notch 102 permitting oscillation of the bar 56 when one of the rods 44 is pulled outwardly of the vending machine. The solenoid S1 is energized by a series of electrical circuits which are made by the insertion of the proper coins hereinafter more fully described.

In Fig. 4 there is shown diagrammatically the coin selectors, switches, solenoids and coin receptacles. The electrical connections between the several parts have not been shown in this view for the purpose of clarity but are shown in Fig. 6. The form of the device selected for illustrat-

ing one adaptation of the invention comprises coin selectors for each of three denominations of coins which may be used and the following description will relate to its use in dispensing articles costing fourteen cents. Three coin selectors are shown, one 106 to receive a dime, another 108 to receive a nickel and another 110 to receive a penny. These selectors are standard units of well-known construction and, per se, form no part of the invention other than in combination with associated parts of the mechanism. The function of such selectors is to separate slugs or imperfect coins from good coins, rejecting the former and permitting the good coins to continue through the operating mechanism.

The good coins are received in coin counters 112, 114 and 116 where they control switches to close certain electrical circuits determined by the number of coins received in the coin counter. When certain of the circuits are completed, the solenoid S1 becomes energized and the plunger 104 is withdrawn from the notch 102. The bar 56 is then free to oscillate out of the notches 66 in the rods 44.

The coins remain in the coin containers until the operator has made a selection of one of the handles 42 and initially moves it outwardly of the machine. The initial movement of one of the rods 44 causes the locking member 100 to oscillate. The outer periphery of the locking member 100 is provided with a raised portion 118 which closes a double pole switch CS1, one pole of which completes an electrical circuit through a solenoid S2. The solenoid S2 operates a gate 120 in a coin chute 122. The coin chute 122 has two passages in its bottom wall, one passage 124 communicating with a container 126 open to the outside of the machine and one passage 128 directed toward a coin receptacle 130 inside the machine.

The gate 120 is normally positioned to direct any coins in the chute 122 to the container 126 accessible to the operator. Prior to the energization of solenoid S2, the coins may be returned as hereinafter more fully explained. When the solenoid is energized, it swings the gate 120 through rack and pinion 132, closing the passage 124 to the outside of the machine and directs the coins through the passage 128 to the coin receptacle 130.

The solenoid S2 has an extension 134 on its core which, during the final movement thereof, closes a switch CS2 completing an electrical circuit through a coin release solenoid S3. This delayed action permits the gate 120 to close the passage 124 before the coins are released. When the solenoid S3 is energized it, acting through rack and pinion 136, raises one sidewall of the coin counters 112, 114 and 116 thereby releasing the coins therein to permit the coins to fall into the coin chute 122. The side walls of the coin counters are hinged as at 138 and form one sidewall of the coin counter passages.

Prior to the deposit of the last coin required to make up the selling price of the item being vended, the operator may operate a push button PB and all coins that have been inserted will be returned through passage 124 to the outside receptacle 126. The push button PB completes an electrical circuit through a solenoid S4 which swings a sidewall of the coin selectors 106, 108 and 110 about the hinges 140 through the rack and pinion 141 releasing any coins therein. The push button PB also completes an electrical circuit through the solenoid S3 and a normally

closed switch CR1² thereby releasing all coins in the coin counters 112, 114 and 116.

Assuming now that the mechanism is set to operate by a total value of coins equaling fourteen cents, the circuits for the different denominations of coins will be seen by reference to Figs. 5 to 11 inclusive. There are four different combinations of coins which total fourteen cents; fourteen pennies, one nickel and nine pennies, two nickels and four pennies, and one dime and four pennies. The last coin of any one of the four combinations completes an electrical circuit through a control relay CR1 which closes the switch CR1¹, energizing the solenoid S1.

In Fig. 5 the coin chutes or passages have been diagrammatically illustrated and except for their shape and location are similar to the usual coin chutes having spaced parallel sidewalls with guiding ribs therebetween forming the chutes.

A dime chute 142 has its lower end closed by a contact controlling support 144. Preferably, the support is a resilient abutment which supports a dime and is movable by the weight of the dime for closing the terminals of a switch COS6.

The nickel chute 146 has its lower end closed by a contact controlling support or abutment 148 similar to the support 144 which by the weight of a nickel closes the terminals to a switch COS3. This chute 146 has a lateral branch chute 150 arranged to receive a second nickel after the first nickel has been deposited in the chute 146, the second nickel being deflected into the chute 150 by impinging upon the first nickel positioned on the support 148. The chute 150 has its lower end closed by a contact controlling support 152 similar to the supports 144 and 148 which by the weight of the nickel closes the terminals to a switch COS5. While the chute 146 extends substantially in a vertical direction, it is slightly offset at its lower end from the vertical in a direction opposite to the side of the chute 150 so that the second nickel will strike on one side of the top center of the first nickel to direct the second nickel into the chute 150.

The penny chute 154 is shown having four branch chutes 156, 158, 160 and 162. The branch chute 156 is substantially in vertical alignment with the chute 154 but is slightly offset in a direction opposite to the chute 158 so that, when the uppermost penny is in the chute 156, it will divert the next penny from the chute 154 into the chute 158. The chute 160 is arranged on a side of the chute 156 opposite to that of the chute 158 and receives the next penny after the uppermost penny in the chute 158 has been inserted. The chute 162 is positioned beyond the chute 160 to receive a penny after the uppermost penny in the chute 160 has been inserted. The lower end of chutes 158, 160 and 162 are each provided with contact controlling supports or abutments 164, 166, and 168 respectively which close the contacts of switches COS1, COS2 and COS4 respectively. The contact controlling supports 144, 152, 148, 168, 166 and 164 with their respective switches are carried bodily by the swinging sidewall of the coin counters 112, 114 and 116 so that, when the coins are to be released by swinging the sidewalls, the bottoms of the coin chutes are removed and the coins fall into the chute 122.

In the form of the invention illustrated, the dime chute 142 is constructed to receive one dime, and the nickel chutes 146 and 150 one nickel each. The penny chute 158 holds five pennies, chute 156 holds three, chute 160 holds five and chute 162 holds one. As the coins are fed into their

respective chutes, the dime closes the switch COS6. The first nickel closes switch COS3 and the second nickel closes switch COS5. The first three pennies fall in chute 156 and the fourth falls in chute 158 closing switch COS1. The next four pennies fall in chute 158 and the ninth penny is directed into chute 160 closing switch COS2. The next four pennies fall into chute 160 and the fourteenth penny falls into chute 162 closing switch COS4.

Referring to Figs. 6 to 11 inclusive, the operation of the machine by any of the various combinations of coins to total fourteen cents will be more fully understood. If the purchaser should desire to use fourteen pennies, the fourth penny closes switch COS1, the ninth closes switch COS2 and the fourteenth closes switch COS4, thus completing an electrical circuit from a source of electrical energy through the control relay CR1. This circuit is illustrated in Fig. 7. If the operator should select a nickel and nine pennies, the nickel closes switch COS3, the fourth penny closes switch COS1 and the ninth penny closes switch COS2, thus completing an electrical circuit through the control relay CR1 as illustrated in Fig. 8. When two nickels and four pennies are used, the first nickel closes switch COS3, the second nickel closes switch COS5 and the fourth penny closes switch COS1, completing the circuit through the control relay CR1, illustrated in Fig. 9. When a dime and four pennies are used, the dime closes switch COS6 and the fourth penny closes switch COS1, completing the circuit through the control relay CR1.

The control relay CR1 closes the switch CR1¹ energizing the solenoid S1 for releasing the plunger 104 and opens normally closed switches CR1² and CR1³ for preventing operation of coin release mechanism, controlled by the release button PB, after the plunger 104 has been withdrawn.

The machine is now in condition for the operator to remove the article of purchase. The initial movement of the rod 44 causes rotary movement of the locking member 100 and the raised portion 118 closes the double pole switch CS1 completing an electrical circuit through solenoid S2 which immediately swings the gate 120 from its position for directing coins to the containers 126 to a position for directing the coins into the coin receptacle 130. The final movement of the extension 134 of the solenoid core closes switch CS2 to complete a circuit through the coin release solenoid S3. This releases the coins in the coin counters 112, 114 and 116 and they fall into the funnel shaped coin chute 122 where they enter the coin receptacle 130 through passage 128.

It is to be noted that when the normally closed switches CR1² and CR1³ are open the solenoid S4 does not operate to release the coins from the coin selectors 106, 108 and 110 but that both solenoids S3 and S4 operate to release the coins from the coin selectors 106, 108 and 110 and the coin counters 112, 114 and 116 when the push button PB is operative.

The double pole switch has been provided to complete a circuit through solenoid S2 through one pole and another circuit through the control relay CR1. This is to maintain the control relay CR1 energized after the coins have been released and the switches COS1 to COS6 inclusive thereby opened.

After the operator has withdrawn a dispensing member from the machine and removes the article of purchase therefrom, the return movement

switch CS1 by a reverse rotation of the locking member caused by the notch 66 in the rod 44 engaging the bar 55. The solenoid S1 is then de-energized and the plunger 104 engages the notch 102.

The above description relates to the operation of the machine by coins having a total value of fourteen cents. However, means has been provided for readily changing the circuits and coin travel so that the machine may be set to operate by different total amounts comprising any combination of coin denominations. For example, if the article is sold for thirteen cents, a peg is inserted in an opening A, Fig. 5, so that the first penny, as it enters the chute 156, is positioned above the peg. For twelve cents, the peg is placed in the opening B; for eleven, in the opening C; and for ten cents, in opening C and an additional peg is placed in the opening D of chute 158. When the pegs are in the openings C and D, it is necessary to maintain the switch COS1 normally closed.

If the machine is to be operated by coins totaling from nine cents to one cent, the leads to COS4 are removed and placed on COS2, the leads to COS2 having been removed and connected together forming a direct connection between COS1 and COS3. This is illustrated in Fig. 11. Operation of the machine by nine pennies is caused by the first three pennies falling in chute 156 and the fourth in chute 158, closing switch COS1; the pegs having been removed. The next four pennies fall in chute 158 and the ninth in chute 160 closing the switch COS2. If a nickel and four pennies are used, the nickel enters chute 146, closing switch COS3. Three pennies enter chute 158 and the fourth enters chute 158, closing switch COS1 and completing the connection through control relay CR1.

The operation of the device for values of eight, seven and six cents is through the same switches as described for nine cents except that a peg is placed in the opening A for eight cents, in B for seven cents and in C for six cents.

For a value of five cents, switch COS1 is shorted retaining the same connections as shown in Fig. 11. When five pennies are used, pegs are placed in openings C and D so that the first four pennies fall in chute 158 and the fifth in chute 160 closing switch COS2 to complete the connection through normally closed switches COS1 and COS2 to energize control relay CR1. Operation by a single nickel closes COS3 completing the connection to control relay CR1.

For values below a nickel, the short across the switch COS1 is removed so that it is operable by the first penny to fall in chute 158.

Values of four, three, two and one cent may cause operation when the switch COS3 is shorted. For operation by four pennies, all pegs are removed, the first three enter chute 156 and the fourth closes switch COS1, completing the connection to control relay CR1. When a peg is placed in opening A, the third penny closes switch COS1; when the peg is in opening B, the second penny closes switch COS1; and when the peg is in opening C, the first penny closes switch COS1.

From the above it will be seen that the machine can be readily set to operate for any value from one to fourteen cents and any selected denomination of coins totaling any one of the values will cause its operation.

Having in mind the general construction and various adjustments provided, an overall analysis

75 of the arrangement employed in the coin actu-

ated control mechanism will be useful. For that purpose let us first of all assume the simple case in which the pegs C and D are in place (Fig. 5) and the coin switch COS1 held closed, all as heretofore described, to condition the mechanism for operation on a total sales price of ten cents. With such a set-up there are, it will be perceived, what may be termed three main chutes 142, 146 and 154 for each of the several denominations of coins. Communicating with each of these main chutes, except the chute 142 for the highest denomination coin, is a branch chute adapted for the automatic diversion into it of the last of a predetermined series of coins dropped into the corresponding main chute. Such branch chutes are shown as 150 and 162. Basically the arrangement is such that the last coin entering any lesser denomination main chute (146 or 154) to make up a total equal to the value of the highest denomination is diverted into the branch chute mentioned. Thus in the case of the lesser denomination main chute 146, the second nickel dropped into it is diverted into its branch chute 150, since this second nickel completes a total value of ten cents. Similarly, the tenth penny dropped into the penny chute 154 is diverted into its branch chute 162.

It will be appreciated that with the arrangement as so far analyzed, entry of an appropriate coin into the dime chute 142 or into one of the branch chutes 150 or 162 indicates the deposit in the mechanism of the same total value of coinage, namely, ten cents. Consequently, a set of what may be termed main switches are arranged to be actuated by such coins, these being shown as coin switches COS6, COS5 and COS4 heretofore described. Actuation of any one of these three main switches serves to operate the control device shown as the solenoid S1, through the agency of the control relay CR1, as heretofore detailed.

It is to take care of the somewhat more complicated situation in which coins of two lesser denominations are dropped into the mechanism to make up the total of the highest denomination that a set of what may be termed auxiliary switches are included. These are shown as the switches COS2 and COS3 heretofore described. There is such an auxiliary switch for each of the lesser denominations of coins and it is arranged to be actuated upon the receipt of the number of coins required to make up the value of the next to the highest one of the series of denominations of coins for the entire series. In the present instance the next to the highest value is five cents and accordingly the auxiliary switch COS2 is arranged to be actuated upon the deposit of the fifth penny, while the other auxiliary switch COS3 is arranged to be actuated upon the deposit of the first nickel. The auxiliary switches are correlated in such a manner (connected in series as shown in Fig. 6) so that upon their simultaneous closure they will serve to effect energization of the main solenoid S1 as an alternative to closure of one of the main switches COS4, COS5 and COS6.

It is to take care of situations in which the total sales price is not a whole number multiple of any but the least coin in the series that what may be termed a supplemental chute and supplemental switch are included. The supplemental chute is shown as 156 and the supplemental switch as the coin switch COS1. Upon removal of the peg D the supplemental switch COS1 is adapted to be operated in response to the deposit of one, two, three or four pennies,

depending upon which one, if any, of the three pegs A, B and C is used. Then by making closure of the supplemental switch COS1 a condition precedent to actuation of the main control device or solenoid S1 by any one of the main switches, or by conjoint action of the auxiliary switches, the special condition is taken care of in which the total sales price is not a whole number multiple of any but the least denomination coin.

It is to be understood that various changes including the size, shape and arrangement of parts may be made without departing from the spirit of my invention and it is not my intention to limit its scope other than by the terms of the appended claims.

I claim as my invention:

1. In a coin actuated device for receiving coins of a given denomination having a plurality of inter-communicating chutes each for receiving in sequence a predetermined number of coins, a hinged member forming a sidewall for said chutes, resilient supports carried by said hinged member forming closure ends for respective ones of said chutes, control devices operable in response to the movement of respective ones of said resilient supports when a coin is received on a corresponding one of said resilient supports, and means for swinging said hinged sidewall away from said chutes to free any coins therein.

2. In a coin actuated control mechanism for vending machines or the like, the combination of a plurality of main chutes each adapted to receive coins of respectively different denominations, all of said main chutes except the one for the highest denomination coin having a corresponding branch chute communicating therewith and arranged for the automatic diversion into such branch chute of the last of a predetermined series of coins entering the main chute, a plurality of main coin switches arranged with one disposed to be actuated by a coin dropped into the highest denomination chute and the others for actuation by coins received in respective ones of said branch chutes, each chute except that for the highest denomination coin having an auxiliary switch associated therewith and operable in response to the receipt of the number of coins required to equal the value of the next to the highest denomination coin in the series, a control solenoid, and means for energizing said solenoid in response to the actuation of any one of said main switches or of all of said auxiliary switches simultaneously.

3. In a coin actuated control mechanism for vending machines or the like, the combination of a plurality of main chutes each adapted to receive coins of respectively different denominations, all of said main chutes except the one for the highest denomination coin having a corresponding branch chute communicating therewith and arranged for the automatic diversion into such branch chute of the last of a predetermined series of coins entering the main chute, a plurality of main coin actuated devices arranged with one disposed for actuation by a coin dropped into the highest denomination chute and the others for actuation by coins received in respective ones of said branch chutes, each chute except that for the highest denomination coin having an auxiliary coin actuated device associated therewith and operable in response to the receipt of the number of coins required to equal the value of the next to the highest denomination coin in the series, a control device, and means for actuating said control

device in response to the actuation of any one of said main coin actuated devices or of all of said auxiliary coin actuated devices simultaneously.

4. In a coin actuated control mechanism for vending machines or the like, the combination of a plurality of coin receivers, one for each of a consecutive series of denominations of United States coins beginning with a penny as the least coin in the series, a plurality of coin actuated devices operable respectively in response to the receipt of each coin deposited in each of said receivers except for the penny receiver, a plurality of additional coin actuated devices associated with said penny receiver, adjusting means for effecting actuation of one of said additional devices in response to the deposit in said penny receiver of from one to four pennies as determined by the setting of such adjustable means, means for effecting actuation of the remainder of said additional devices in response to the deposit in said penny receiver of respective different multiples of five pennies in addition to the number preset by said adjustable means, a control device, and means for operating said control device in response to actuation of any combination of various ones of said coin actuated devices corresponding to a predetermined total value of coins.

VICTOR G. SMITH.
